US00D671554S

(12) **United States Design Patent** (10) **Patent No.:** **US D671,554 S**
Woo (45) **Date of Patent:** **** Nov. 27, 2012**

(54) **DISPLAY SCREEN WITH GRAPHICAL USER INTERFACE**

(75) Inventor: **Aaron N. Woo**, Seattle, WA (US)

(73) Assignee: **Microsoft Corporation**, Redmond, WA (US)

(**) Term: **14 Years**

(21) Appl. No.: **29/384,438**

(22) Filed: **Jan. 31, 2011**

(51) **LOC (9) Cl.** **14-04**

(52) **U.S. Cl.** **D14/487**

(58) **Field of Classification Search** **D14/485-495; 715/700-867**

See application file for complete search history.

(57) **CLAIM**

The ornamental design for a display screen with graphical user interface, as shown and described.

DESCRIPTION

FIG. 1 is a front view of a display screen with graphical user interface showing my new design; and,

FIG. 2 is a front view of the display screen of FIG. 1 shown on a device.

The broken line showing of the remainder of the display screen, three squares, and the text in FIGS. 1 and 2, and the remainder of the device in FIG. 2 is for environmental purposes only and forms no part of the claimed design.

1 Claim, 2 Drawing Sheets
